TOILET FLUSHING APPARATUS

Benjamin T. Ezzell, Harlingen, Tex.

Application September 18, 1951, Serial No. 247,089

2 Claims. (Cl. 4—57)

1

This invention relates to flushing mechanisms for toilets. More specifically, the invention has reference to a mechanism of the type stated novelly designed in a manner to insure proper seating of the ball valve.

In most instances, a relatively short valve rod is utilized in equipment of the type stated. Conventionally, the valve rod passes through one guide only. As a result, the ball valve, when elevated, moves erratically in or on top of the swirling water, as the water escapes from the flush tank.

In many instances, the proper reseating of the valve is dependent upon the action of a small whirlpool centered upon the valve seat, which becomes evident as the water within the flush tank nears exhaustion after opening of the valve. Or, independently of or in combination with said whirlpool, a partial vacuum may be set up within the valve seat, which tends to seat the valve properly.

However, in actual practice, water is rushing into the flush tank through the intake valve, and will be at its maximum flow just at the moment immediately preceding the time for closing of the ball valve, since at this time the float operating the intake valve will be at its lowest position. As a result, the heavy flow of water through the intake valve on many occasions causes the ball valve to be forced off center, as a result of which it fails to seat properly when it drops to closed position. In such instances, of course, the mechanism continues to flush until the difficulty is remedied.

It is the main object of the present invention to provide a mechanism of the character described which will be effective to cause the ball valve to seat properly in each and every instance.

Another important object is to provide, in a mechanism of the type stated, a valve rod guide arrangement wherein the rod is guided as to sliding movement thereof by a pair of vertically aligned guides, placed as far apart as the depth of the tank will permit, the valve rod being lengthened accordingly. In this way, the valve 45 will be held in proper alignment, and will tend to seat itself properly on many more occasions than is true of the present arrangement, wherein a single guide is utilized in association with a short valve rod.

It is a further important object to use, in combination with the paired guides and elongated valve rods, a means controllable by the float rod that will bind the valve rod against its associated guide during the time during which the ball valve 55

2

is to remain unseated, thus to hold the ball valve immovably while elevated above the valve seat, and prevent its being acted upon by the swirling incoming water.

5 A further important object is to provide a mechanism of the character described which can be incorporated with a minimum of difficulty in flushing mechanism already in use.

Yet another important object is to provide apparatus as stated which can be manufactured at relatively low cost, will be simple in construction, and will be sure in operation.

Other objects will appear from the following description, the claims appended thereto, and from the annexed drawing, in which like reference characters designate like parts throughout the several views, and wherein:

Figure 1 is a view of a flush tank partly in side elevation and partly in longitudinal section, a mechanism formed in accordance with the present invention being illustrated in side elevation, the dotted lines indicating the unseated position of the parts;

Figure 2 is a top plan view in which portions have been broken away;

25 Figure 3 is a vertical sectional view taken substantially on line 3—3 of Figure 1; and

Figure 4 is a perspective view of a weight control link embodied in the invention.

Referring to the drawings in detail, at 10 I have designated a conventionally formed flush tank, having the overflow pipe 12 mounted therein in the usual position.

Secured to the overflow pipe 12 is a lower guide 14 extending laterally from the pipe and disposed a comparatively short distance above the bottom wall of the flush tank. The lower guide is aligned vertically with an upper guide 16, secured to the overflow pipe in comparatively closely spaced relation to the upper end of said pipe.

The upper guide 16 is formed with an upwardly offset end 18, having formed thereon the guide ring 20, that is aligned vertically with and is spaced a substantial distance from a lower guide ring 22 provided upon the lower guide 14.

An elongated, straight valve rod 24 has up and down sliding movement in the guide rings 20, 22, and secured to the lower end of the rod 24 is a conventionally formed rubber ball valve 26. Intermediate opposite ends of the rod 24, a collar 28 is formed upon said rod, said collar being engageable by a lift ring 30, that is slidable upon the rod 24 and is pivotally connected to the lower end of a lift rod 32, having a pivotal connection at its upper end to the pivoted operating lever 34.

50 The operating lever 34 is fulcrumed upon the side

wall of the flush tank 18, and is rigid with an operating handle 36 disposed exteriorly of the tank and adapted to set the flushing mechanism into operation when shifted to the dotted line position thereof illustrated in Figure 1.

Secured to the upper guide 16, and projecting laterally therefrom, is a pivot pin 38 on which is rockably mounted a sleeve 40 formed intermediate opposite ends of a weighted arm 42. Upon one end of the arm 42 is a weight 44 which 10 is in the present instance, but not necessarily, is in the shape of a round ball. The weight 44, normally frictionally engages the valve rod 24, so as to bind the valve rod against the upper and lower guide rings 20, 22 respectively, the 15 valve rod and valve ball in their elevated positions, as illustrated in dotted lines in Figure 1.

Upon the other end of the arm 42, I form a laterally disposed eye 46, receiving a hook 48 formed upon the upper end of a weight control rod 50. The rod 50 is illustrated in Figure 4, and may comprise a single piece of stout rod material bent to shape. In the illustrated example of the weight control means, the rod 50 is formed intermediate opposite ends thereof with a return bend 52, merging into a reversely extended end portion 54 having at its free end a lateral extension 56 hooked around the main portion of the rod 50.

A conventional float arm 58 is provided at one end with a float 60, the arm 58 being fulcrumed upon a suitable bracket, and being adapted to control the seating and unseating of the intake valve 62. This is conventional construction, and it may be noted at this point that in some instances, the fulcrum point of the float arm 58 is spaced a substantial distance above the bottom of the tank, rather than close to the bottom as in the illustrated example.

In any event, regardless of the location of its fulcrum, the float arm 58 is extended through the opening 64 defined in the control link 50, and is shiftably upwardly and downwardly within said opening as the water rises and falls in the flush tank.

In use, the weight 44 will normally tend to gravitate to a position in which it engages the valve rod 24. When the operating handle 36 is shifted to the dotted line position illustrated in Figure 1, the valve rod 24 will be elevated, to unseat the ball valve 26, and permit the water within the flush tank to escape. The weight 44, of course, will still tend to gravitate into a position against the rod 24, and will bind the rod against the guides 20, 22 in the elevated position of the rod, thus to hold the ball valve in a fixed position and prevent its being moved erratically from a proper position under the action of the swirling water.

When the water is fully exhausted, the ball or float 60 will have dropped to its lowermost position, and the float arm 58 will engage the return bend portion 52 of the weight control link 50, at the proper moment. This causes the weight 44 to be swung upwardly out of engagement with the valve rod 24, so that the ball valve will drop straight downwardly to its seat.

It believe it is entirely possible that instead of a rigidly formed weight control rod 50, a flexible member such as a chain could be utilized, connected at opposite ends to the float arm 58 and to the weighted arm 42. The chain, in this instance, would be of such a length as to cause the chain to be drawn taut when the float arm 58 is lowered to substantially the bottom limit

of its travel, with the result that the weight 44 will be swung upwardly from the valve rod 24 in the manner previously described herein.

It is believed to be an important characteristic of the present invention that the mechanism utilized is one that can be manufactured at relatively low cost, and can be readily embodied in flushing mechanisms already in use. It is further of importance, it is thought, that the apparatus is one which though inexpensive, obtains a highly desirable result, mainly the proper seating of the ball valve 26 in each and every instance, which is of importance in halting the flushing action at the proper time.

It is believed clear that the invention is not necessarily confined to the specific use or uses thereof described above, since it may be utilized for any purpose to which it may be suited. Nor is the invention to be necessarily limited to the specific construction illustrated and described, since such construction is only intended to be illustrative of the principles of operation and the means presently devised to carry out said principles, it being considered that the invention comprehends any minor changes in construction that may be permitted within the scope of the appended claims.

What is claimed is:

1. In combination, a toilet tank having a bottom, an overflow pipe rising from said bottom and having an upper end, a flush valve seat on said bottom, a flush valve for said seat including a valve rod rising from said valve, said overflow pipe and said valve rod being in laterally spaced relation to each other, a lower valve rod guide fixed on said overflow pipe, an upper valve rod guide fixed on said overflow pipe near the upper end of said overflow pipe, said lower and upper guides having guide rings through which said valve rod is slidably engaged, a water inlet valve seat on said tank bottom, a float valve arm pivoted intermediate its ends on said inlet valve seat, an inlet valve on one end of said float valve arm for said inlet valve seat and a float on the other end of said float valve arm, an operating lever pivoted on the tank, a lift rod pivoted on said operating lever and depending alongside of said flush valve rod, a stop on said flush valve rod, said lift rod being slidably connected to said flush valve rod at a point below said stop, a friction arm pivoted intermediate its ends on said upper valve rod guide, said friction arm having an outer end arranged to bear frictionally against said flush valve rod for holding said flush valve rod in an elevated open position, positioning means associated with said friction arm in holding engagement with the flush valve rod, and an operative connection between said float valve arm and said friction arm serving to pivot said friction arm out of holding engagement with said flush valve rod as said float valve arm descends from an elevated position toward a depressed position.

2. In combination, a toilet tank having a bottom, an overflow pipe rising from said bottom and having an upper end, a flush valve seat on said bottom, a flush valve for said seat including a valve rod rising from said valve, said overflow pipe and said valve rod being in laterally spaced relation to each other, a lower valve rod guide fixed on said overflow pipe, an upper valve rod guide fixed on said overflow pipe near the upper end of said overflow pipe, said lower and upper guides having guide rings through which said valve rod is slidably engaged, a water inlet valve seat on said tank bottom, a float valve arm

pivoted intermediate its ends on said inlet valve seat, an inlet valve on one end of said float valve arm for said inlet valve seat and a float on the other end of said float valve arm, an operating lever pivoted on the tank, a lift rod pivoted on said operating lever and depending alongside of said flush valve rod, a stop on said flush valve rod, said lift rod being slidably connected to said flush valve rod at a point below said stop, a friction arm pivoted intermediate its ends on said upper valve rod guide, said friction arm having an outer end arranged to bear frictionally against said flush valve rod for holding said flush valve rod in an elevated open position, positioning means associated with said friction arm in holding engagement with the flush valve rod, and an operative connection between said float valve

arm and said friction arm serving to pivot said friction arm out of holding engagement with said flush valve rod as said float valve arm descends from an elevated position toward a depressed position, said positioning means comprising a weight on the said outer end of the friction arm.
